VENDING-MACHINE.

No. 882,923.

Specification of Letters Patent. Patented March 24, 1908.

Application filed April 3, 1907. Serial No. 366,135.

To all whom it may concern:

Be it known that we, EDGAR B. BICKER and CHARLES R. SCHILLING, both citizens of the United States, residing at St. Louis, Missouri, have invented a certain new and useful Improvement in Vending-Machines, of which the following is a full, clear, and exact description, such as will enable others skilled in the art to which it appertains to make and use the same, reference being had to the accompanying drawings, forming part of this specification, in which—

Figure 1 is a front elevation of our improved vending machine, a portion of the casing being broken away to show the construction of the ejecting device located therein; Fig. 2 is a detail view showing a portion of the machine with the lid of the casing tilted back; Fig. 3 is a vertical sectional view taken 20 on the line 3—3 of Fig. 1; Fig. 4 is a sectional view taken on the line 4—4 of Fig. 1; and Fig. 5 is a horizontal sectional view taken on the line 5—5 of Fig. 1.

This invention relates to coin-controlled machines, and particularly to that type which are used for vending articles of merchandise.

The main object of our invention is to provide a machine of simple construction that comprises few parts and which can be manufactured at a small cost.

The machine herein shown, which represents the preferred form of our invention, is provided with a receptacle for holding the articles to be vended, a rotatable ejecting device for carrying the articles from the receptacle to a point where they can be picked up by the purchaser, and means for permitting said ejecting device to be rotated only when a coin of the proper denomination is inserted in the machine.

Referring to the drawings, 1 designates a box-like casing in which the ejecting device is mounted, said casing also constituting the till or money box of the machine. The casing is provided with a hinged cover 2 that carries the receptacle 3 which holds the articles to be vended. The machine herein shown is designed for vending small glass tubes 4 filled with candy pills, such as are used for perfuming the breath but it will, of course, be understood that the machine could be used for vending cigars or various other articles. The receptacle 3 is in the form of a long chute provided with a glass

panel 5 and having its lower end open, as shown in Figs. 1 and 3. An ejecting device 5^a is rotatably mounted in the casing 1 and closes the lower end of the receptacle 3, said ejecting device consisting of a cylinder provided with a plurality of grooves or slots 6 into which the articles drop from the receptacle 3, this cylinder being preferably made of hardwood and having two longitudinal grooves formed therein, as shown in Figs. 1 and 2.

A horizontal shaft 7 is journaled in the end walls of the casing and the ejecting device 5^a is loosely mounted on said shaft. Rigidly connected to this shaft 7 is a disk 8 that is located in alinement with a slot 9 in the lid of the casing through which the coin is inserted to permit the ejecting device to become operative, said disk being provided with two grooves 10 of a proper width to receive a coin 11. The ejecting device is provided with two pins 12 that project toward the coin-receiving disk 8 but do not engage the same. When a coin is mounted in one of the slots 10 of the disk 8, however, said coin will engage one of the pins 12 and will thus impart rotary movement to the ejecting device whenever the shaft 7 is turned by means of the handle 13 on the outer end thereof, thereby causing the article which is seated in the groove 6 in said ejecting device to be carried into position where it can drop onto the receiving chute 14, as shown in dotted lines in Fig. 3, the periphery of the ejecting device preventing the articles from dropping out of the opening at the lower end of the receptacle 3. The ejecting device 5^a is retained in position so that one of its slots 6 is in alinement with the opening at the lower end of the receptacle 3 by means of a spring-actuated lever 15 that bears against a flat-faced portion at one end of the cylinder 5^a, this flat-faced portion preferably consisting of a rectangular-shaped block 16 so that two faces will be provided for coöoperating with the lever 15. The shaft 7 is also retained in position so that one of the slots in the coin-receiving disk 8 will be in alinement with the slot 9 through which the coin is introduced, by means of a spring-actuated lever 17 that coöperates with a rectangular-shaped block 18 on the shaft 7, these levers 15 and 17 being controlled by coiled springs 15^a and 17^a, as shown in Figs. 3 and 5.

The block 16 on the ejecting device is so formed that it will permit the lever 15 to spring back to normal position and thus return the ejecting device to normal position 5 slightly in advance of the operation of the lever 17, the purpose of this being to carry the pin 12 on said ejecting device, which is in engagement with the coin, out of contact with said coin before the disk 8 has arrived 10 in position to permit the coin to drop onto the bottom of the receptacle 3.

To prevent the ejecting device from being rotated a number of times by means of a coin that has become wedged in the slot 10 15 in the coin-receiving disk, a stop 18^a is secured to the underneath side of the lid 2 of the casing in the path of movement of the disk 8, as shown in Fig. 4. The machine is also provided with means for preventing the 20 ejecting device from being actuated by a washer or metal slug, this means consisting of a magnet 19 secured to the underneath side of the lid 2 of the casing. When a washer or metal slug is inserted in the slot 9 25 this magnet 19 will attract it and thus draw it far enough away from the pin 12 on the ejecting device so that it cannot engage said pin and thus rotate the ejecting device when the shaft 7 is rotated. The lid 2 carries a 30 hasp 20 that extends over a staple 21 on the front wall of the casing, a padlock 22 passing through said staple to prevent the lid from being raised.

Having thus described our invention, what 35 we claim as new and desire to secure by Letters Patent is:

1. In a vending machine, a cylindrical ejecting device, an operating shaft upon which said device is loosely mounted, a disk rigidly connected to said shaft adjacent one end of the ejecting device and provided with a slot extending longitudinally of the shaft to receive a coin, a pin or stud projecting laterally from the ejecting device and 45 adapted to be engaged by the coin mounted in-said disk, and a pair of spring-actuated levers co-operating with portions on the operating shaft and on one end of the ejecting device for holding them in predetermined 50 positions; substantially as described.

2. A vending machine comprising a receptacle for holding the articles to be vended, an ejecting device, an operating shaft having a coin-receiving member rigidly connected 55 thereto, means on said ejecting device for causing it to be moved only when a coin is mounted in said member, and a stationary stop arranged in alinement with the coin-receiving member and adapted to be engaged by a coin that has become lodged 60 therein for preventing said coin from actuating

the ejecting device more than once; substantially as described.

3. A vending machine comprising a rectangular-shaped casing provided with a hinged lid, a receptacle secured to said lid for holding the articles to be vended and being open at its lower end, a horizontal shaft journaled in the end walls of said casing, a cylinder loosely mounted on said shaft and provided with a plurality of recesses for receiving the articles from said receptacle, a disk rigidly connected to the operating shaft adjacent one end of said cylinder and provided with a plurality of slots disposed longitudinally of the shaft to receive coins, projections on the end of the cylinder that are adapted to be engaged by a coin in one of the slots of said disk and thus transmit the rotary movement of the shaft to the cylinder, a chute into which the articles are discharged from said cylinder, means for holding the cylinder and the operating shaft in position so that only one recess of the cylinder is in alinement with the lower end of the receptacle, and a rigid stop on the underneath side of the lid of the casing arranged in alinement with the coin-receiving disk for preventing the shaft from making more than one complete revolution when a coin has become wedged in the coin disk; substantially as described.

4. A vending machine consisting of a casing having a hinged cover, a receptacle carried by said cover and having its lower end open, said cover also being provided with a coin slot, a horizontal operating shaft journaled in the walls of the casing, an ejecting device loosely mounted on said shaft for receiving articles from said receptacle, a disk secured to said operating shaft in alinement with the coin slot in the lid of the casing and provided with a plurality of cross slots for holding coins, pins on one end of the ejecting device projecting toward the coin-receiving disk, a pair of spring-actuated levers co-operating with flat-faced portions on the ejecting device and operating shaft, a stop on the underneath side of the lid of the casing arranged in alinement with the coin-receiving disk, and a magnet on the underneath side of said lid at one end of the coin slot to withdraw a slug or washer out of alinement with the pins on the ejecting device; substantially as described.

In testimony whereof we hereunto affix our signatures in the presence of two witnesses, this thirtieth day of March 1907.
